(57) **CLAIM**

The ornamental design for an electronic device cover, as shown and described.

DESCRIPTION

FIG. 1 is a first perspective view of a first embodiment of an electronic device cover in a first position, taken from above; FIG. 2 is a second perspective view of the first embodiment of the electronic device cover of FIG. 1, taken from below; FIG. 3 is a front view of the first embodiment of the electronic device cover of FIG. 1; FIG. 4 is a back view of the first embodiment of the electronic device cover of FIG. 1; FIG. 5 is a right-side view of the first embodiment of the electronic device cover of FIG. 1; FIG. 6 is a left-side view of the first embodiment of the electronic device cover of FIG. 1; FIG. 7 is a bottom view of the first embodiment of the electronic device cover of FIG. 1; FIG. 8 is a top view of the first embodiment of the electronic device cover of FIG. 1; FIG. 9 is a first perspective view of a second embodiment of an electronic device cover in a first position, taken from above; FIG. 10 is a second perspective view of the second embodiment of the electronic device cover of FIG. 9, taken from below; FIG. 11 is a front view of the second embodiment of the electronic device cover of FIG. 9; FIG. 12 is a back view of the second embodiment of the electronic device cover of FIG. 9; FIG. 13 is a right-side view of the second embodiment of the electronic device cover of FIG. 9; FIG. 14 is a left-side view of the second embodiment of the electronic device cover of FIG. 9; FIG. 15 is a bottom view of the second embodiment of the electronic device cover of FIG. 9; and, FIG. 16 is a top view of the second embodiment of the electronic device cover of FIG. 9.

(Continued)

The broken lines showing portions of the electronic device cover form no part of the claimed design.

1 Claim, 12 Drawing Sheets
